PAINT PAIL BRACKET

Frederick W. Oldenburg, Harper Woods, Mich.

Application March 11, 1958, Serial No. 720,787

5 3 Claims. (Cl. 248—211)

This invention relates to pail supporting brackets, and more particularly to a bracket device for supporting a paint bucket, or the like, on a ladder.

The main object of the invention is to provide a novel and improved pail supporting bracket for use with a ladder, said bracket being simple in construction, being easy to mount on a ladder, and providing a secure and reliable support for a bucket of paint, or the like, attached thereto.

A further object of the invention is to provide an improved pail supporting bracket for use with a ladder, said bracket being arranged so that it may be used either at the right or left side of the ladder, the device involving relatively inexpensive components, being durable in construction, and being provided with means for locking the handle element of a pail thereto so that the pail cannot accidentally become dislodged or detached therefrom, and so that the ladder, with the bracket and pail attached thereto, may be easily moved from one location to the other.

Further objects and advantages of the invention will become apparent from the following description and claims, and from the accompanying drawing, wherein:

Figure 1 is a front elevational view of a pail supporting bracket constructed in accordance with the present invention, shown with a fragmentary portion of a ladder to which the bracket is to be attached.

Figure 2 is a horizontal cross-sectional view taken on the line 2—2 of Figure 1, but showing the locking lever of the bracket in its locking position.

Figure 3 is a vertical cross-sectional view taken on the line 3—3 of Figure 2.

Figure 4 is an end elevational detail view of the main bar member employed in the bracket device of Figures 1 to 3, said view being taken on the line 4—4 of Figure 1.

Figure 5 is a fragmentary top plan view of the main bar member of the bracket device, said view being taken on the line 5—5 of Figure 1.

Figure 6 is a front elevational view, on a reduced scale, of a ladder provided with a pail supporting bracket, as illustrated in Figures 1 to 5, and showing the manner in which a paint bucket is supported by the bracket device.

Referring to the drawings, 11 generally designates an improved pail supporting bracket assembly according to the present invention. The bracket assembly 11 comprises a main bar member 12 formed with a U-bend 13 adapted to receive the side rail 14 of a ladder 15, one end portion of the main bar member 12 being provided with a hook member 15 rigidly secured to its edge, said hook member being adapted to receive a rung 16 of the ladder at a portion of said rung adjacent to the side rail 14, as illustrated in Figures 1 and 2. Thus, the U-bend 13 may be formed adjacent one end of the main bar member 12, as illustrated, whereby an end tab 17 is defined between the U-bend 13 and the end edge of the bar member 12. The hook member 15 comprises a generally U-shaped strip of flat metal which is welded at one end thereof to the top edge of the tab 17, as shown at 18 in Figure 3. The open end of the hook member 15 is lo-

2

cated rearwardly, as is the open end of the U-shaped element 13.

The outwardly extending arm portion of the main bar member 12 is formed with the transversely extending flange 19, said flange being formed with a vertical slot 20 opening at the top edge of the flange, as is clearly shown in Figures 4 and 5.

Designated at 21 is a straight locking lever which is substantially coextensive in length with the main bar member 12 and which is pivotally connected to said main bar member at a point outwardly adjacent the U-bend 13, as by a rivet 22. The outer end portion of the locking member 21 is notched away at its lower corner, as shown at 23, to define a locking lug 24 which is engageable in the vertical slot 20 when the locking lever 21 is rotated to a horizontal position adjacent the main bar member 12. The notch 23, however, is of sufficient height so that the wire bail handle 25 of a bucket 26 may be received in the slot 20 below the lug 24 when the top edge of the locking lever 21 is in its horizontal position, substantially flush with the top edge of the main bar member 12.

A headed rivet member 26 is rigidly secured in the tab element 17 of the main bar member 12 and projects rearwardly therefrom, as shown in Figure 2. The inner end portion of the locking member 21 is formed with an arcuate slot 27 in which the shank portion of the headed rivet member 26 is receivable when the locking lever 21 is rotated to its horizontal position, shown in Figures 2 and 3.

In using the bracket device, the U-shaped member 13 is first engaged with one side rail 14 of the ladder and the hook element 15 is engaged on a rung 16 at the desired height on the ladder. The handle bail 25 of the bucket 26 is then engaged in the slot 20, and the locking lever 21 is then rotated from the position thereof shown in Figure 1 to its horizontal position, whereby the lug 24 enters the upper portion of slot 20 above the bail 25 and whereby the slot 27 lockingly engages with the shank portion of the headed rivet 26, frictionally locking the lever 21 in its horizontal position wherein the top edge is flush with the top edge of the main bar member 12. As shown in Figure 2, the locking lever 21 also frictionally engages the rear surface of the side rail 14 of the ladder, so that the U-shaped member 13 is dimensioned to snugly receive the side rail. Thus, the bracket device is securely fastened to the ladder and secures the bucket handle 25 so that the bucket is fastened to the ladder and cannot accidentally become detached therefrom.

As is readily apparent, the bracket may be applied either to the right side of the ladder or to the left side thereof, since the device may be engaged with the left side rail of the ladder by merely reversing the position thereof shown in Figure 6.

While a specific embodiment of an improved pail supporting bracket device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A pail supporting bracket comprising a main bar member formed with a U-bend adapted to receive the side rail of a ladder, a hook member secured to the top edge of one end portion of said main bar member and adapted to receive a rung of the ladder, the opposite end portion of said main bar member being formed with a transversely extending flange, said flange being formed with a vertical slot opening at the top edge of said flange, defining a hook adapted to supportingly receive the bail of a paint bucket or the like, a locking lever pivoted to

the main bar member, means on one end portion of said locking lever engageable in said vertical slot when said locking lever is adjusted to a position substantially parallel to the main bar member, and means on the other end portion of said locking lever lockingly engageable with said main bar member when the locking lever is in said position.

2. A pail supporting bracket comprising a main bar member formed with a U-bend adapted to receive the side rail of a ladder, a hook member secured to the top edge of one end portion of said main bar member and adapted to receive a rung of the ladder, the opposite end portion of said main bar member being formed with a transversely extending flange, said flange being formed with a vertical slot opening at the top edge of said flange, defining a hook adapted to supportingly receive the bail of a paint bucket or the like, a locking lever pivoted to the main bar member, a lug on one end portion of said locking lever engageable in said vertical slot when said locking lever is adjusted to a position substantially parallel to the main bar member, a locking projection on said one end portion of the main bar member, and means on the other end portion of said locking lever lockingly engage-

able with said locking projection when the locking lever is in said position.

3. A pail supporting bracket comprising a main bar member formed with a U-bend adapted to receive the side rail of a ladder, a hook member secured to the top edge of one end portion of said main bar member and adapted to receive a rung of the ladder, the opposite end portion of said main bar member being formed with a transversely extending flange, said flange being formed with a vertical slot opening at the top edge of said flange, defining a hook adapted to supportingly receive the bail of a paint bucket or the like, a locking lever pivoted to the main bar member, a locking projection on said one end portion of the main bar member, and a lug on one end portion of said locking lever engageable in said vertical slot when said locking lever is adjusted to a position substantially parallel to the main bar member, the other end portion of said locking lever being formed with a slot arranged to receive and lockingly engage with said locking projection when the locking lever is in said position.
